UNITED STATES PATENT OFFICE.

ANDY KULIKOFF, OF PITTSBURGH, PENNSYLVANIA.

PADLOCK.

1,398,233.

Specification of Letters Patent. Patented Nov. 29, 1921.

Application filed May 3, 1921. Serial No. 466,452.

To all whom it may concern:

Be it known that I, ANDY KULIKOFF, a citizen of Russia, residing at North Side Pittsburgh, county of Allegheny, and State 5 of Pennsylvania, have invented certain new and useful Improvements in Padlocks, of which the following is a specifications.

This invention relates to improvements in padlocks and particularly to padlocks adapted to be operated without the use of a key.

It is the principal object of the invention to provide a padlock of this type which can be opened and closed through the operation of two movable buttons by a person knowing 15 the secret.

Another object of the invention is the provision of a padlock of this character which is closed automatically.

These objects are attained by the novel 20 construction and combination of parts hereinafter described and shown in the accompanying drawing, forming a material part of this disclosure, and in which—

Figure 1 is a front view of the padlock 25 constructed according to my invention.

Fig. 2 is an inner rear view thereof after the removal of the cover seen in the direction of line 2—2, Fig. 3.

Fig. 3 is a vertical section through the 30 lock on line 3—3 of Fig. 1.

The padlock comprises a casing 10, having front and rear plates 11 and 12 respectively and a shackle 13.

The front plate 11 shows the customary 35 key hole 14 and four buttons 15, 16, 17 and 18 respectively. The button 15 is movable and can be moved vertically in the direction of the lower end of the lock casing 10, while the buttons 16 and 18 are stationary. The 40 button 17 is also movable horizontally toward the outer left hand side edge of the casing 10.

The rear wall 12 of the casing is provided with an inner depression 19, in which are 45 slidably arranged, as shown in Fig. 2, the vertical latch 20 on one side of the casing, and the horizontal latch 21 near the upper edge thereof.

The pin 22 of the knob or button 15 slides 50 within a vertical recess 23 in the front wall of the casing of a size equal to the size of the radius of the underside of button 15. This pin is secured with its inner end to the latch 20, and a spring 24 is vertically disposed in 55 the depression 19 abutting with one end against the lower edge of said depression

and with the other against a shoulder 25 of the latch 20, and on its upper edge the latch 20 has a finger or projection 26 engaging in a suitable recess of the latch 21. The horizontal latch 21 has a latch projection 27 on one of its ends adapted to engage in the projected position of the latch 21 the keeper opening of the shackle 13 as indicated in Fig. 2. At its opposite end the latch 21 is 60 provided with a shoulder 28 against which abuts one end of a horizontal spring 29, the other end of which rests against the side edge of the depression 19. The button 17 has a pin 30 secured with its inner end to 65 the latch 21 and adapted to be laterally displaced in a slot 31 of the front wall 11 of casing 10, said slot being of a size equal to the length of the radius of the underside of button 17.

The rear wall 12 of the casing shows also four buttons, two of which, 15' and 18', are shown in Fig. 3, which however are decoy buttons only.

The lock operates as follows—

Assuming the lock is locked, as illustrated in Fig. 2, and it is desired to open the same, then the person knowing the secret moves the knob 15 toward the lower edge of the casing and this will also move the latch 20 85 downward against the action of spring 24, while the finger or projection 26 at the opposite end of the latch will be disengaged from the recess in latch 21.

When now the operator moves knob or 90 button 17 toward the left the latch 21 will be moved against the action of spring 29 and its projection 27 will be disengaged from the keeper opening of the shackle 13, which can now be swung around its pivot 32 and the 95 lock will be open. The operation of closing the lock will be clear from the above description without further explanation.

Having thus described my invention, what I claim as new, and desire to secure by Letters Patent of the United States is—

1. A padlock of the class described comprising a casing and a shackle, two sliding latches in said casing, a means for normally holding one of said latches in locking engagement with the other latch, a means for normally holding one of said latches in engagement with the shackle of said lock, and means for successively disengaging one of said latches from the other, and the other 110 latch from the shackle.

2. A padlock of the class described com-

prising a casing having a depression in its inner rear wall, and a shackle, a vertical and a horizontal latch sliding in the depression of said casing, a spring for normally pressing said horizontal latch into engagement with said shackle, a spring for normally holding said vertical latch in engagement with said horizontal latch, and means for successively interrupting the engagement between both latches and between one of said latches with the shackle.

3. A padlock of the character described comprising a slotted casing having a depression in its inner rear wall, and a shackle, two latches slidably displaceable in the depression of said casing, a plurality of buttons on the outer front and rear walls of said casing, two of said buttons movable, pins for said movable buttons sliding in the slots of said casing, and secured with their inner ends to said latches, springs for normally pressing one of said latches into locking engagement with the other, and the other latch into locking position with the shackle, the operation of said movable buttons adapted to engage successively the engagement between both latches and between one of said latches with said shackle for allowing an opening of the lock.

4. In a padlock of the class described having a slotted and depressed casing, a shackle pivotally secured with one end in said casing and provided with a keeper opening at its opposite end, a recessed horizontal latch sliding in the depression of said casing, a finger on one end of said latch adapted to engage the keeper opening of said shackle, a spring normally holding said finger in engagement with the keeper opening, a recessed, vertical latch also sliding in the depression of said casing, a finger on the upper end of said vertical latch engaging a recess in said horizontal latch, a spring for normally holding said finger in engagement with the recess of said horizontal latch, pins on said latches sliding in the slots of said casing and projecting through the same toward the outside, buttons on the outer ends of said pins permitting a displacement of the same in the slots for operating said latches, said slots being of a length equal to the radius of the lower faces of said pins, and a plurality of immovable decoy buttons on the front and rear faces of the casing covers.

In testimony whereof I affix my signature.

ANDY KULIKOFF.
